LIFTING JACK

Samuel A. Snell and William H. Schomburg,
Toledo, Ohio, assignors to The Bingham
Stamping & Tool Company, Toledo, Ohio, a
corporation of Ohio

Application April 6, 1932, Serial No. 603,552
17 Claims. (Cl. 254—103)

This invention relates to a class of devices known as lifting jacks and more particularly to a type of lifting jack utilizing a screw means for obtaining lift.

5 The invention embraces a lifting jack of the character embodying movable threaded members for obtaining exceptionally long lift in proportion to the size and height of the device when in collapsed or lowered position.

10 The invention contemplates the provision of simple and effective means cooperating with the screw members for permitting independent successive movement of the screw members.

15 A further object of the invention is the provision of a lifting jack casing or housing fabricated of sheet material wherein the various parts of the device are assembled and retained in fixed relation by simple and inexpensive means affording a construction light in weight with exceptional rigidity to withstand strains arising through the operation of the device.

20 Still another object is the provision of a casing or standard for the lifting jack fabricated in such a manner as to retain the various movable parts 25 of the lifting jack in assembled relationship without the use of additional means.

25 Further objects and advantages are within the scope of this invention such as relate to the arrangement, operation and function of the related 30 portions of the structure, to various details of construction and to combination of parts elements per se, and to economies of manufacture and numerous other features as will be apparent from a consideration of the specification and drawings 35 of a form of the invention, which may be preferred, in which:

Figure 1 is a vertical section view of the device of our invention;

Figure 2 is a horizontal section view taken substantially on the line 2—2 of Figure 1;

Figure 3 is a substantially horizontal sectional view taken on the line 3—3 of Figure 1;

Figure 4 is a horizontal section view taken substantially on the line 4—4 of Figure 1.

45 While we have shown our invention as embodied in a lifting jack particularly of the character adaptable for use in elevating automotive vehicles for the changing of tires, repairs and the like, it is to be understood that our invention 50 is not limited to the particular construction as illustrated nor the uses mentioned, but that we contemplate modified constructions and other uses of the invention wherever the same may be found to be applicable.

55 Referring to the drawings in detail, the device

5 consists of a standard or casing structure 10, which in the embodiment illustrated comprises two similar upright sections 11 and 12 and a base plate 13. Each section 11 and 12 is provided adjacent its lower extremity with horizontal integral base portions 17, having upwardly turned flanges 18. These sections are also formed with upright semi-cylindrical portions 19 which, when the sections are assembled, form a tubular housing or guide for the lifting screw members. A 10 plurality of re-enforcing hollow ribs 20 and 21 are formed on the sections and serve to strengthen the structure, making the base portion 17 rigid with respect to the upright semi-cylindrical portions 19.

15 It may be desirable to utilize an additional base plate 13 having a peripheral flange 25 which snugly fits the flange 18 of the sections 11 and 12, the base plate 13 and the base portions 17 of the sections being held together preferably by spot welding, as at 24. By this means the base structure 20 is made exceptionally strong and rigid and will not distort when exceptionally heavy loads are elevated by means of the lifting jack of our invention.

25 Positioned within the tubular guide 22 formed by portions 19 through the assembly of sections 11 and 12 is an outer threaded member or screw 27 which is provided with a cylindrical bore 28 throughout the major portion of its length, the upper internal portion of the member 27 being threaded as at 29, this threaded portion supporting an inner screw member 30. The inner screw 30 supports at its upper extremity a load carrying element 31 having an irregular uppermost contour to facilitate engagement with the load element to be lifted, the member 31 being provided with an opening which snugly fits over a tenon 32 formed on the upper end of the screw 30, the projecting portion of the tenon being swaged as at 36 to hold the member 31 in fixed relationship with respect to the screw 30.

35 The upper end of the standard 10 formed of sections 11 and 12 is provided with an annular recess or hollow portion 33 within which is positioned a driving nut 34, the latter being internally threaded to cooperate with the threads on the exterior surface of screw 27, this nut 34 also being formed with gear teeth 35. The teeth 35 are in mesh with teeth 37 of a driving pinion 38 which is journaled in a tubular bearing portion 39 formed as an integral lateral extension of the upper portion of standard 10. Positioned immediately beneath the nut 34 is a bearing race or annulus 40 which contains a pin- 40 45 50 55

rality of bearing balls 41, the latter engaging a race or thrust plate 42, which is supported upon outwardly extending shoulder portions of the sections 11 and 12 forming the recess 33.

5 The driving pinion 38 is formed with an enlarged circular outer portion 46 having an internal circular hollow portion 47 and a rectangular slot 48 in the outermost wall of portion 46, the slot being particularly adapted to admit the 10 end of an operating handle or member of usual construction (not shown), which is suitably adaptable for rotating the driving pinion in a manner well known in the art. The driving pinion 38 is formed with an axially central bore 50 15 and a second axial bore of reduced diameter 51. Slidably arranged within the latter bore 51 is a pin-like member 52 having a head 53. The driving pinion 38 also supports a transversely extending pin 54, and positioned between the pin 20 54 and the head 53 of pin 52 is an expansible coil spring 55. The extremity of pin 52 is adapted to engage the outer periphery of the bearing race 40, the latter being preferably provided with a depression or detent 57 for suitable frictional coaction with the pin 52 in a manner to be 25 hereinafter explained.

One of the features of applicants' invention lies in the simplicity of assembly of the various parts which will now be described. The bearing 30 races 40 and 42 and bearing balls 41 are first disposed within the semi-annular recess in one of the sections 11 or 12. The nut 34 and the outer and inner screws 27 and 30 have been previously 35 assembled as follows: A stop pin 58 is first driven in position in the lower end of the inner screw 30 and the inner screw threaded into the outer screw 27, after which the member 31 is fitted over the tenon 32 of the inner screw and the latter swaged as at 36 to retain the member 31. The 40 outer screw 27 is then threaded into the driving nut 34 and the extreme end threads of the outer screw 27 are distorted in a manner (not shown) to prevent the removal of the nut with respect to the outer screw.

45 The entire assembly of inner and outer screws and nut 34 is then placed in position in the recess 33 and the bore formed by the tubular portion 19, the screws 27 and 30 projecting through the bearing annulus 40. The driving pinion 38 is then 50 placed in its proper position after which the other section of the two similar half sections 11 and 12 is fitted in position and the flanges thereof spot welded or otherwise held together by suitable means as at 15. In the assembly of the 55 casing structure, the two similar sections 11 and 12 are preferably temporarily spot welded as at 15 to hold the parts in fixed relation after which rivets 16 are applied forming a permanent rigid arrangement. It is to be understood however, 60 that any suitable fastening means may be utilized as for example spot welding may be applied at several points in lieu of the rivets 16, or other suitable means may be employed to hold the parts 11 and 12 together. The driving pinion 38 when 65 inserted in the final assembly is already provided with the pin 52 and the spring 55 arrangement as has been hereinbefore explained. After the sections 11 and 12 have been secured together, the outer base plate 13 may be secured to the structure by spot welding as hereinbefore explained. The sections 11 and 12 are provided with flange 70 portions 60 adjacent the upper extremity thereof which engage the upper surface of the driving nut 34 to prevent the removal thereof through the open end of the casing or standard. In the

manner above described, the entire assembly of parts is retained by means of the securing of the two sections 11 and 12 together.

The operation of the device is as follows:

The jack structure is placed beneath the axle 5 of the vehicle or other load to be elevated with member 31 in a position to engage the load during the elevation of the screw members. The handle member (not illustrated), is inserted through the slot 48 into the hollow portion 47 of 10 the driving pinion 38, the latter being then rotated by the handle, the teeth of the pinion driving the nut 34. Due to the expansive pressure of the coil spring 55 upon pin 52, the pin frictionally engages a detent 57 in the annulus or ball race 40, 15 thus urging a portion of the inner wall of the bearing annulus into frictional contact with the threads of the outer screw 27. This friction means normally prevents the screw 27 from rotating during the driving action of the pinion 38 in 20 emeshment with the nut 34. A rotation of the pinion 38 in the proper direction causes the nut 34 to turn relative to the threaded member 27, the latter being elevated because rotation is normally prevented through the friction of the pin 52 25 engaging the bearing annulus 40. The outer screw member 27, inner screw 30, and member 31 will be elevated as a unit until the lowermost thread on the member 27, which has been distorted to 30 prevent the member 27 from screwing entirely through the drive nut, engages the lower surface of the driving nut 34. Thereafter, further rotation of the driving nut 34 will overcome the friction of the pin 52 in the detent 57, and nut 34 and threaded member 27 will thereafter rotate 35 as one unit. Due to the fact that the member 31 is in engagement with the axle or other load to be lifted, rotation of the inner screw 30 is prevented by reason of the weight of the article to be lifted, the outer screw 27 rotating with nut 34 40 will then cause the elevation of the inner screw 30, and the latter may be elevated until such time as the pin 58, carried by the lower end of the inner screw engages the end wall of the enlarged bore 28 within the outer screw 27, which of course 45 determines the maximum lift of the jack.

To lower the jack from the elevated or extended position of the screws, the pinion 38 is rotated in the opposite direction. The threaded member 27 will then be non-rotatable with respect to the 50 nut 34, by reason of the pin 52 again engaging the detent 57 in the ball race 40 and the member 27 will be lowered until the uppermost thread, which has been previously distorted to act as a stop, engages the upper surface of the nut 34. 55 When the member 27 has reached this lowermost position, it will rotate with the nut 34 as a unit overcoming the friction of pin 52 with detent 57, and due to the relative rotation of threaded member 27 with respect to the internal screw 30, the latter will be then lowered as continued rotation of the pinion 38 takes place until such time as the upper screw is lowered away from the load.

It is apparent that, within the scope of the 60 invention, modifications and different arrangements may be made other than is herein disclosed, and the present disclosure is illustrative merely, the invention comprehending all variations thereof.

70 What we claim is:

1. In a device of the character disclosed; a standard; a plurality of telescopically arranged members movable within said standard; an anti-friction bearing supporting one of said members; 75

- and means engageable with said bearing for controlling movement of one of said members.
2. A lifting jack comprising a standard; a rotatable driving member supported on said standard; an antifriction bearing positioned between said driving member and said standard; a plurality of telescopically arranged threaded members associated with said driving member; and means co-acting with said bearing for controlling the movement of said threaded members.
3. A lifting jack comprising a standard; a rotatable driving member supported on said standard; an antifriction bearing positioned between said driving member and said standard; a plurality of telescopically arranged threaded members associated with said driving member; and friction means co-acting with said bearing for controlling the relative rotation of said threaded members with respect to the standard.
4. In a device of the character disclosed, in combination a standard formed of sheet material and having a tubular portion; a threaded member movable in said tubular portion; a driving nut for said threaded member; a bearing supporting said driving nut; a pinion journaled upon said standard and co-operating with said driving nut; and means interposed between said pinion and said bearing for controlling the movement of said threaded member.
5. In a device of the character disclosed, in combination a standard formed of sheet material and having a tubular portion; a threaded member movable in said tubular portion; a driving nut for said threaded member; a bearing supporting said driving nut; a pinion journaled upon said standard and co-operating with said driving nut; and means carried by said pinion and engageable with said bearing for controlling the movement of said threaded member.
6. A lifting jack comprising a sheet metal casing, certain portions of said casing having flanges; means for securing said flanges together to provide a reenforced tubular guide; an integral lateral extension formed on said casing to provide a cylindrical tubular bearing; a lifting element guided for movement in said casing; a driving element mounted for rotation in said bearing; and means carried by said driving element and cooperatively associated with the lifting for controlling the movement of said lifting element.
7. A lifting jack comprising a sheet metal casing, certain portions of said casing having flanges; means for securing said flanges together to provide a reenforced tubular guide; an integral lateral extension formed on said casing to provide a cylindrical tubular bearing; a threaded lifting element guided for movement in said casing; a driving nut therefor; a driving pinion cooperating with said nut and mounted for rotation in said bearing; and means carried by said driving pinion and cooperatively associated with the lifting element for controlling the movement of said lifting element.
8. A lifting jack comprising a sheet metal casing, certain portions of said casing having flanges; means for securing said flanges together to provide a reenforced tubular guide; an integral lateral extension formed on said casing to provide a cylindrical tubular bearing; a lifting element guided for movement in said casing; a driving element mounted for rotation in said bearing; and means carried by said driving element cooperatively associated with the lifting element for controlling the movement of said lifting element,
- said casing having a re-enforcing flanged base member secured thereto.
9. A lifting jack comprising a sheet metal casing, said casing being formed of similar sections, said sections having flanges; means for securing the flanges of said sections together to provide a re-enforced tubular guide; an integral lateral extension formed on said casing to provide a cylindrical tubular bearing; a lifting element guided for movement in said casing; an antifriction bearing supporting said lifting element; a driving element mounted for rotation in said tubular bearing; and means carried by said driving element and engageable with said antifriction bearing for controlling the movement of said lifting element.
10. A lifting jack comprising a standard; a rotatable interiorly threaded driving nut mounted in the standard, said driving nut having a toothed portion; a screw threaded into said driving nut; a second screw threaded into the first mentioned screw; a driving pinion journaled in said standard meshing with the teeth on said driving nut; and cooperating means interposed between said pinion and outer screw for normally resisting rotary movement of the latter by yielding to permit the outer screw to turn with the driving nut when at the limits of its vertical movement.
11. A lifting jack comprising a standard; a rotatable interiorly threaded driving nut mounted in the standard; an antifriction bearing cooperating with said nut, said driving nut having a toothed portion; a screw threaded into said driving nut; a second screw threaded into the first mentioned screw; a driving pinion journaled in said standard meshing with the teeth on said driving nut; and means carried by said pinion cooperating with the bearing for normally resisting rotary movement of the outer screw by yielding to permit the outer screw to turn with the driving nut when at the limits of its vertical movement.
12. A lifting jack comprising a sheet metal casing, said casing being formed of similar sections, each section having flanged portions; means for securing the flanged portions together, said casing being formed with a vertical tubular bore and a transversely extending bearing portion; a lifting element positioned in said vertical bore; a driving nut for said lifting element enclosed within said casing; a driving means for said driving nut journaled in said bearing portion, each section being formed with a flange at its upper end engageable with the upper surface of said nut for retaining the latter in position, and each section of said standard being provided also at its lower extremity with an integrally formed transversely extending base portion, said base portion having peripheral flanges; and re-enforcing ribs integrally formed on each section connecting the base portion with the upright tubular portion.
13. In a device of the character disclosed, in combination, a standard; a lifting element in said standard; a driving nut therefor; a pinion cooperating with said driving nut; and means carried by said pinion and cooperatively associated with said lifting element for controlling movement of said lifting element.
14. In a device, of the character disclosed, in combination, a standard; a lifting element in said standard; a driving nut therefor; a pinion cooperating with said driving nut; and means carried by said pinion and resiliently urged into

- said cooperative association with said lifting element for controlling the movement of the lifting element.
15. A lifting jack comprising a sheet metal casing, said casing being formed of similar sections, each section having flanged portions; means for securing the flanged portions together, said standard being formed with a vertical tubular bore and a transversely extending bearing portion; a lifting element positioned in said vertical bore; a driving means for said lifting element journaled in said bearing portion, each section of said standard being provided at its lower extremity with an integrally formed transversely extending base portion, each base portion having peripheral upwardly projecting flanges, a base plate having similarly formed peripheral flanges arranged to contact with the flanges on said base portions in telescopic relation.
16. In a device of the character disclosed, a standard; a plurality of telescopically arranged members rotatably supported within said standard; a bearing supporting one of said members; and resilient means engageable with said bearing for urging the latter into frictional engagement with one of said members for controlling the rotation thereof.
17. In a device of the class disclosed, a standard; an outer screw member and an inner screw member disposed within said standard; a bearing surrounding and supporting said screw members; means for rotating said screw members; and means for engaging the bearing for urging the latter into frictional contact with the outer screw member for controlling the rotation of said screw members.
